United States Patent Office.

RICHARD C. HARRIS, OF HARRISVILLE, NEW JERSEY.

Letters Patent No. 91,842, dated June 29, 1869.

IMPROVED MACHINE FOR MAKING PAPER.

The Schedule referred to in these Letters Patent and making part of the same.

Be it known that I, RICHARD C. HARRIS, of Harrisville, in the county of Burlington, and State of New Jersey, have invented certain new and useful Improvements in Machines for Making Paper; and I do hereby declare that the following is a full, clear, and exact description of the construction and operation of the same, reference being had to the annexed drawings, making part of this specification, in which—

Figure 1 is a section of the improved machine;

Figure 2, a longitudinal section of the apparatus, without my improvements;

Figure 3, a plan, showing the two forming-cylinders and the improved agitators; and

Figure 4, a front view of the improved carrier-roll, pressure-roll and gutter, showing also the tub M and coucher-arms n in section.

The invention relates to that apparatus known as the "double-cylinder machine," and in order to convey a correct idea of what is admitted as old, and what is claimed as new, there are shown two views of the machine, of which fig. 1 is a longitudinal section of the improved apparatus, and fig. 2, a representation of the machine before the improvements were made.

The periphery of the cylinders b and b' is made of wire cloth, as usual, and the air and water being constantly exhausted from their interior, a sheet of fibres attaches itself to the wire cloth, and is carried, by the slow revolution of b and b', figs. 1 and 2, underneath the pressure-cylinders, or couchers a and a', figs. 1 and 2.

In the old style of the apparatus, fig. 2, only the coucher a' is placed at a considerable distance toward the left from the vertical line c d, so that the water, which is expressed from the partially-formed sheet x', will run down on the left side of b', and not on the right, where x' ascends, the roller e, at the same time, keeping the felt apron f from having too much contact with the cylinder b'.

It will be noticed that this roller e supports nothing but the apron f, and as the sheet x', which is kept to the lower side of the apron f, whilst passing from b' to b, with the latter, by atmospheric pressure, prevents the elevation of the apron by means of a solid roller, like e, the coucher a has, in the old style of machine, always been placed perpendicularly above b, causing the water thereby to run down on the right side of b, against and through the partially-formed sheet x, in consequence of which "water-marks" and other imperfections occur in the paper.

It has been attempted to obviate this difficulty, by applying a splash-board, g, fig. 2, intended to lead off the water at the sides of the machine, but it was abandoned on account of the wear and tear of the apron and wire-cloth, occasioned by the friction against it.

The improvement consists in an arrangement which enables me to elevate the sheet x' and apron f, before

they enter between the cylinder b and coucher a, fig. 1, so that the coucher a can be moved toward the left, similar to a'.

A solid roller, like e, cannot be used, because the felt apron f, permitting the air to pass through its body to a certain extent, would allow the sheet x' to adhere to a solid roller, on account of the atmospheric pressure having more effect upon the solid surface of the latter. Hence, it is necessary to provide a roller, E, fig. 1, whose periphery will permit the passage of air through it, somewhat more freely than the apron f, and I have found wire cloth of the proper fineness to be a very suitable article for this purpose; but felt of less density than that of the apron f, or a similar material, may be used.

By the tension of the sheet x' and apron f upon the roller E, and by the pressure of the small solid roller F, figs. 1 and 4, some water is forced out of the sheet x', which is carried off to the side of the machine by the gutter G, underneath the roller E.

The gutter is provided with spouts G' on each end, as shown in fig. 4, from which the water may be led off to any desired place.

Another great advantage of placing the coucher a, fig. 1, in the same relative position as a' is, that a certain pressure, (the weight of the parts for example,) forcing the coucher in the perpendicular direction of the arrow l, will produce more effect in uniting the two sheets x and x' between a and b, than the same pressure would, if applied and acting in a line joining the centres of a and b, as in fig. 2.

The agitators o o, when placed horizontally, as in fig. 2, cause dirt, sand, and other foreign substances, to rise in the pulp, thereby injuring the quality of the paper, and as their motion is in the same plane as that of the paper, their tendency is to arrange the fibres of the latter longitudinally, causing the paper to be weaker in that direction than it is transversely.

The improved agitators p p, figs. 1 and 3, consist of prongs w w, fastened in the arms of the spiders u, which are fastened to the vertical shafts v.

These shafts run in bearings s s, and are driven by spur-wheels t, or other suitable means.

The plane of motion of these agitators being at or nearly at right angles to that of the motion of the paper, the fibres are properly interlocked, producing a paper equally strong in all directions, and as there are no upward currents produced, all that foreign matter, which is of greater specific gravity than the pulp, remains at the bottom of the tub.

Any suitable number of agitators may be placed in the tub n, as shown in fig. 3, where the dotted lines t t t represent the pitch-circles of the spur-wheels t, which gear into each other and run in the direction of the arrows, fig. 3; but I do not confine myself to any particular way of giving motion to the agitators, as that may be varied to suit circumstances.

The mechanical appliances for that purpose are too well known to need any description.

One of these contrivances, however, is shown in plan, fig. 3, where mitre-wheels t^1 are used, gearing into similar ones t^2 on the shaft r , which runs in bearings s s' , fastened to the edges of the tub n .

A pulley, r' , gives motion to the whole by means of a belt.

I do not claim as my invention, any of the parts, nor any of the combinations shown in fig. 2; nor do I claim agitators whose axis is vertical, apart from paper-making machines; but

What I claim as my invention, is—

1. The arrangement of the roller E with the couch-

er a , fig. 1, when the periphery of the roller E is made of wire cloth or its equivalent, substantially as and for the purpose specified.

2. The combination of the roller E , roller F , gutter G , and spouts $G' G'$, with the apron f , and coucher a , substantially as and for the purpose specified.

3. The combination of the vertical agitators p p , with a "double-cylinder machine," fig. 1, substantially as and for the purpose set forth in this specification.
